UNITED STATES PATENT OFFICE.

RICHARD H. WILLIAMS, OF MOUNT VERNON, NEW YORK.

DESIGN FOR A KALEIDOSCOPE-BOX.

SPECIFICATION forming part of Design No. 25,391, dated April 14, 1896.

Application filed February 27, 1896. Serial No. 581,072. Term of patent 7 years.

To all whom it may concern:

Be it known that I, RICHARD H. WILLIAMS, a citizen of the United States, residing at Mount Vernon, in the county of Westchester and State of New York, have invented and produced a new and original Design for Kaleidoscope Boxes or Cases, of which the following is a specification.

This design has for its object to provide a novel form or shape of kaleidoscope box or case which presents a characteristic appearance to the eye.

The leading feature of my design consists in a kaleidoscope box or case having three flat sides, each of which is in the form of a trapezoid, two of the trapezoidal sides having two right angles, an obtuse angle, and an acute angle, and the other trapezoidal side having two acute angles and two obtuse angles.

The design is illustrated by the accompanying drawings, in which—

Figure 1 is a perspective view of the kaleidoscope box or case, and Figs. 2 and 3 are detail views illustrative of the side plates of the box or case.

The kaleidoscope box or case comprises three flat side plates A, B, and C, each of

which is in the form of a trapezoid. The trapezoidal side plates A and B are alike in form and have equal dimensions, and each is provided with two right angles 10 and 11, an obtuse angle 12, and an acute angle 13, as best seen in Fig. 2. The trapezoidal side C is provided with two acute angles 14 and 15 and two obtuse angles 16 and 17, as best seen in Fig. 3. The trapezoidal side plates A, B, and C are arranged, as shown in Fig. 1, to form a truncated pyramid, which is shown as lying on its trapezoidal side plate B. The inner faces of the trapezoidal side plates are provided with reflector-surfaces 18, 19, and 20.

The design provides a kaleidoscope box or case of a peculiar form or shape, which presents a characteristic appearance.

45

What I claim is—

The design for a kaleidoscope box or case, substantially as shown.

In testimony whereof I have hereunto set my hand in the presence of two subscribing witnesses.

RICHARD H. WILLIAMS.
